United States Patent Office

Des. 227,460
Patented June 26, 1973

227,460

VITAMIN TABLET OR SIMILAR ARTICLE

Ian C. Modelevsky, Pleasantville, Benjamin S. De Young, Sands Point, and Donald Nevins, East Elmhurst, N.Y., and Anthony Stern, Mexico City, Mexico, assignors to Bristol-Myers Company, New York, N.Y.

Filed June 27, 1972, Ser. No. 266,763

Term of patent 14 years

Int. Cl. D1—01; D28—01
U.S. Cl. D16—3

FIG. 1 is a front elevational view of a vitamin tablet or similar article embodying our new design;

FIG. 2 is a top plan view thereof;

FIG. 3 is a right elevational view thereof;

FIG. 4 is a bottom plan view thereof;

FIG. 5 is a left elevational view thereof.

We claim:

The ornamental design for a vitamin tablet or similar article, as shown.
